Jinkichi Hikida
By his Attorney
Samuel S. Darby

UNITED STATES PATENT OFFICE.

JINKICHI HIKIDA, OF TOYAMA-KEN, JAPAN.

TUBE-CLEANER FOR MARINE BOILERS.

1,228,437.

Specification of Letters Patent.

Patented June 5, 1917.

Application filed September 7, 1916. Serial No. 118,795.

To all whom it may concern:

Be it known that I, JINKICHI HIKIDA, a subject of the Emperor of Japan, residing at Toyama-Ken, Japan, have made a certain 5 new and useful Invention in Tube-Cleaners for Marine Boilers, of which the following is a specification.

This invention relates to tube cleaners for marine boilers.

10 The object of the invention is to provide a device which is simple in structure and efficient in operation for cleaning the interior surface of tubes, for example marine boiler tubes.

15 A further object of the invention is to provide a device of the class described which shall be easy to insert into a tube and which can be drawn out of the same without difficulty.

20 A further object of the invention is to provide a device of the class described which may be inserted over the tube end of the combustion chamber so that the soot will be swept out toward the smoke box instead of 25 the combustion chamber.

Further objects of the invention will appear more fully hereinafter.

The invention consists substantially in the construction, combination, location and relative arrangement of parts all as will be 30 more fully hereinafter set forth as shown by the accompanying drawing and finally pointed out in the appended claims.

Referring to the drawings.

35 Figure 1 is a view in side elevation of a device constructed in accordance with this invention.

Fig. 2 is a plan view of the same positioned in a boiler tube.

40 Fig. 3 is a view in side elevation of the same.

Fig. 4 is a view in end elevation of the same.

45 Fig. 5 is a view in cross section of the same on the line 5, 5, Fig. 3.

The same part is designated by the same reference numerals wherever it occurs throughout the several views.

The tube cleaning device, in accordance 50 with this invention is comprised of an upper member 1 terminating in a screwed portion 2 at one end and an adjustable lower member 3.

The lower member 3 is adjustably attached to the upper member 1 by upwardly projecting portions 4, formed at or near

each end of the member 3 seating in vertical slots 5 formed in the upper member 1 and secured therein by means of suitable pins 6 to allow a certain amount of movement, between the respective members 1 and 3.

60 Springs 7 coiled around the projections 4 and between the two members 1 and 3 tend to keep the said two members apart, but upon insertion in the tube the springs are 65 compressed by contact of the members 1 and 3 with the inner surface of the tube to permit entry therein and to keep the members 1 and 3 in close contact with the inside 70 of the tube 8.

The edge of a semicircular plate 9 carried by the upper member 1, serves as a cleaner or scraper and acts upon the inner surface of the tube 8. The semicircular plate 9 may be removed and is held in position by a wedge 75 piece 10 driven in between the upper member and the flat surface of the plate 9. A bolt and nut 11 may be used if desired to tighten up the wedge.

A cleaner or scraper is formed upon the 80 lower member 3 as at 12 and is preferably integral therewith.

Secured to the upper member 1 at 13 is a hinged flap 14 which extends transversely across the device. The hinged flap 14 is 85 slotted vertically from its lower or outer edge as shown at 15, to allow it to pass over the lower member 3 as shown best in Fig. 1. In its normal position the flap 14 hangs vertically and the lower cleaner or scraper 12 90 forms a stop to prevent it from swinging past the same when the cleaner is withdrawn. As the cleaner is passed into the tube this hinged flap 14 swings on its hinge as shown in dotted lines in Fig. 3 and passes over the 95 scale or other dirt dislodged by the cleaners, but on the backward or withdrawing stroke of the cleaning device it is forced to its vertical position and serves to rake or draw out all the soot and scale in the tube. 100

Two guide arms 16 and 17 are arranged one at each side of the device and are secured at one end to the sides of the rear part of the upper member 1 at 18. Their forward ends are free and are curved inwardly. 105 At their widest expanse these arms make contact with the inner surface of the tube adjusting themselves to diameter and any inequalities of the bore thereof.

A handle as shown at 19 or any other convenient means for operating the cleaning device may be employed.

Having now described the construction and operation of my device, what I claim as new and useful, and of my own invention, and desire to secure by Letters Patent, is,—

- 5 1. In a tube cleaner device, the combination with an upper member and a removable cleaner therefor, means for adjustably attaching said cleaner to said upper member of an automatically adjustable lower member, a scraper therefor means for adjustably attaching the lower member to the said upper member, and a swinging flap hinged to and dependent from the said upper member.
- 10 2. The combination with a fixed member, a scraping device carried thereby, a movable member loosely secured to said fixed member means interposed between said members to normally separate the same, and a scraping device carried by said movable

member, a hinged flap carried by said fixed member, and adapted to extend over said movable member, and means for limiting the movement of said flap.

- 15 3. The combination with a fixed member, a scraping device carried thereby, a movable member loosely secured to said fixed member means interposed between said members to normally separate the same, and a scraping device carried by said movable member, a hinged flap carried by said fixed member, and adapted to extend over said movable member, and means carried by said movable member for limiting the movement of said flap.

In testimony whereof I have hereunto set my hand this 5th day of September, A. D. 1916.

JINKICHI HIKIDA.
